UNITED STATES PATENT OFFICE

2,493,973

THROAT PLATE FOR CORN SHELLERS

Leslie W. Jones, Beemer, Nebr.

Application July 21, 1947, Serial No. 762,455

1 Claim. (Cl. 130—6)

1

This invention relates to an improvement in corn shellers of the type in which the cobs and shucks are forced through a throat opening controlled by means of a rotatable, spring-actuated cone damper. In shellers of this type the throat opening wears away rapidly from abrasion with the cobs, shucks, and foreign materials in the sheller.

The principal object of this invention is to provide a renewable throat plate which can be placed about the throat opening in the sheller to return it to its original size, and to prevent further wear and tear thereon.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a horizontal section through a conventional corn sheller of the type to which the invention is applicable, taken on the line 1—1, Fig. 2; and

Fig. 2 is a vertical cross-section therethrough, taken on the line 2—2, Fig. 1, illustrating the invention in place therein.

In Fig. 1, typical elements of a conventional corn sheller are designated by numeral as follows: sheller housing 10, cob compartment 11, steel rod shelling cage 12, rotary beater-type shelling head 13, drive shaft 14, shuck distributing beater 15, partition plate 16, cone damper 17 and cover 22.

In the usual corn sheller the steel rod shelling cage 12 is supported at each of its extremities in four arcuate quadrant members 20, in which the extremities of the rods 12 are secured.

These quadrant members 20 are clamped to the partition plate 16 by means of suitable bolts 21 there being three bolts in each quadrant member.

The partition plate 16 has a circular throat opening 18 surrounding the damper 17. The damper 17 is spring cushioned and allows the shucks and cobs to exit from the sheller housing 10 into the cob compartment 11.

The circumference of the throat opening 18 constantly wears away from abrasion with the material passing through the throat opening, due

2

to the pressure and rotation of the damper 17. The opening therefore rapidly wears larger so as to prevent accurate control, resulting in loss of corn.

5 This invention comprises an annular, flat, steel throat plate 19 having an inner diameter equaling the original inner diameter of the throat opening 18. The improved throat plate 19 is positioned between the partition plate 16 and the quadrant members 20 and is clamped between the two by means of the clamping action of the bolts 21. The throat plate 19 acts as a reinforcement for the throat opening 18 and renews the latter to its original size and condition.

10 It is preferred to form the throat plate of thicker material than the partition plate 16 so that it will better resist wear and erosion. However, should it wear it can be easily renewed and replaced by simply loosening the bolts 21.

15 While a specific form of the improvement has been described and illustrated herein, it is desired to be understood that the same may be varied, within the scope of the appended claim, without departing from the spirit of the invention.

20 Having thus described the invention, what is claimed and desired secured by Letters Patent is:

In a corn sheller, the combination of a partition plate having a throat opening; an annular throat plate lying against one face of said partition plate and outlining said opening; arcuate rod-supporting members lying against said throat plate; bolts clamping said arcuate members against said throat plate and said throat plate against said partition plate; and a cylindrical series of steel rods mounted in said arcuate members and forming a shelling cage.

LESLIE W. JONES.
